UNITED STATES PATENT OFFICE.

PHILIP J. DUERR, OF BUFFALO, NEW YORK.

DESIGN FOR AN ORNAMENTAL CHAIN.

SPECIFICATION forming part of Design No. 26,265, dated November 17, 1896.

Application filed May 4, 1896. Serial No. 590,231. Term of patent 7 years.

To all whom it may concern:

Be it known that I, PHILIP J. DUERR, a citizen of the United States, residing at Buffalo, in the county of Erie and State of New York, have invented and produced a new and original Design for Chains, of which the following is a specification, reference being had to the accompanying drawing, showing a part thereof.

This invention relates to a design for ornamental chains, such as watch and fob chains.

The accompanying drawing is a perspective view of a fob-chain embodying the design.

The leading feature of my design consists of a chain which is composed of solid members having the form of plates or tablets and interposed links or flexible connections arranged at or near the side edges of the solid members.

A represents the solid members of the chain, formed by plates or tablets which are substantially rectangular in form and which may be made of any ornamental stone, such as oynx, opaline, or lapis lazuli or of any suitable artificial stone.

b represents the links, arranged near the

side edges of the solid members and projecting beyond the opposing edges thereof, and c are rings or loops which join the links of adjacent solid members. The connecting members at or near the same edge of the chain are arranged in line with each other, and the two rows of connections are parallel with each other and with the edges of the chain, as shown in the drawing. The links b have ornamental inner ends and the links and the rings c may be made of gold or other suitable metal. This produces a very attractive chain, which is especially pleasing as a fob-chain, although the design is equally desirable for other ornamental chains and for bracelets.

What I claim is—

The design for a chain, substantially as herein shown and described.

Witness my hand this 8th day of April, 1896.

PHILIP J. DUERR.
